BUILDING CONSTRUCTION

Sterling Johnston, Bethlehem, Pa., assignor to
McClinic-Marshall Corporation, a corporation
of Pennsylvania

Application September 24, 1931, Serial No. 564,831

11 Claims.

(Cl. 20—16)

My invention relates to the doors of large buildings, particularly of hangars used for the housing of aircraft, and has for one of its principal objects the provision of a door structure which in its open position will cause the minimum undesirable disturbance of the air currents in the vicinity of the building. In one embodiment of the invention, a pair of doors are employed at each end of the hangar, these doors being supported on individual carriages which are moved on rails entirely away from the building and the doors then turned about a vertical axis so as to present their edges to the wind. As a further improvement a shape of door may be chosen which will in such position cause a minimum production of eddy currents in its wake.

In addition to this important object certain advantages in structure and control are also obtained as will be more fully apparent from the description.

Fig. 1 is a front elevation of a door and its supporting carriage.

Fig. 2 is a vertical section along the line 2—2 of Fig. 1.

Figs. 3 and 4 are horizontal outline sections through the door on the lines 3—3 and 4—4 of Fig. 1.

Fig. 5 is a detail of the mechanism for rotating the door.

Figs. 6, 7, and 8 are side and front elevations and plan of the hangar end with the doors in their closed position.

Fig. 9 is a plan of the hangar end showing other positions of the doors.

Figs. 10 and 11 illustrate diagrammatically certain alternative arrangements of the invention.

Fig. 12 shows supplementary apparatus used in controlling the doors.

Fig. 13 illustrates diagrammatically a further alternative arrangement of the invention.

Fig. 14 is a detail of door and hangar construction.

Referring to Figs. 1—5 which represent one specific embodiment of the invention, 11 is one of a pair of doors used for closing an end of a hangar. The door is constructed with an internal skeleton of structural members 12 covered with an outer curved sheath of sheet metal or other material 13. The door diminishes both in width and thickness from the bottom to the top, but is so designed that a "streamline section" is maintained throughout as shown by the outline sections, Figs. 3 and 4. The weight of the door is carried by central pivot 14 located on the top of mast 15 which in turn is rigidly se-

cured to carriage 16. Guiding ring 18, fastened to the lower portion of the door, rolls against a circle of rollers, one of which is shown at 19, this arrangement cooperating with pivot 14, preventing any motion of the door in relation to the carriage except rotation about the pivot axis. Roller 19 revolves on eccentric 27 keyed to shaft 28, which in turn is held in bearing block 29 bolted to the frame of carriage 16. A rotation of shaft 28 causes a radial adjustment of roller 19, such adjustment being used for purposes of original line-up and correction for wear. Setscrew 30 serves to hold shaft 28 in its adjusted position. Ring gear 20 also fastened to the lower portion of the door, concentric with guide ring 15 18, meshes with pinion 21, which through shaft 22, worm wheel 23, worm 24 and shaft 25 is actuated by motor 26, this motor, therefore, serving to rotate the door in relation to the carriage. Worm 24 may be made irreversible in order to hold the door against wind pressure in any position or a separate brake may be provided for the purpose. Bolt 38, sliding in guide 39, secured to the carriage, and adapted to enter socket 40, fastened to a portion of the door structure, serves to lock the door in the rotational position it must occupy in closing the hangar.

Carriage 16 is provided with a set of flanged wheels 31 which roll on track 32, motor 33, acting through train of gears 34, causing this movement in either direction along the track. Power for operating motors 26 and 33 is furnished through insulated third rail 35.

Sheet metal apron 36 covers the working parts of the carriage and with extensions 37 on the bottom of the door forms an effective closure at this point when the doors are in position against the hangar. Furthermore, pads or flaps of resilient material may be provided between the edges of the doors and the hangar and between the two doors. In Figs. 3 and 4, 42 represents a pad, one of which is attached to the edge of each door where they contact with each other, while the other edge 41 contacts with pads attached to the edge of the hangar opening. The construction is shown more in detail in Fig. 14. Here 41, the tapering edge of door 11, is in contact with pad 75 attached to member 74 which is a portion of the hangar end. The pad consists of an inner spring construction 76 enclosed in 50 a resilient outer covering 77.

Figs. 6 and 7 are side and front elevations and Fig. 8 is a plan of an end of hangar 52 with doors 50 and 51 in the closed position. It will be seen that the end of the building terminates in a blunt 55

wedge in each face of which is located one member of the pair of doors. Tracks 32 for the carriages are laid at right angles to the longitudinal axis of the building, movement of the carriages outwardly along these tracks opening the end of the hangar. One of the carriages and doors in the position it would have just after such movement is shown at 50, Fig. 9.

Although the fact that the doors are moved away from the immediate vicinity of the hangar would in itself tend to lessen the effect of eddy currents formed in their wake, with fairly strong winds these would still be serious. The revolution of the doors about their axes, however, makes it possible to align them so that they present an edge to the wind, and thus reduce eddy currents. Furthermore the "streamline" section to which they are designed still further and very greatly improves the condition.

The term "streamline section" as here used is understood to refer to the section ordinarily given to fins, struts and other members employed in aircraft construction where the intention is to minimize air resistance and eddy currents. Although considerable variation in exact shape is permissible, in general it may be described as a flattened section formed of curved lines, or a combination of curved and straight lines, which from a thick middle portion converges fore and aft either to acute angled or rounded ends. It has been found in practice that the forward end on which the air current first impinges may be made quite blunt even a semi-circle of diameter equal to the full width of the section, but that the after end should have a long taper and terminate either in an acute angle or a curve of small radius. The center of gravity of the area of the section may therefore be in the middle of the longitudinal axis of the section or be considerably displaced along this axis. The ratio between width and length of the section can be varied between reasonably wide limits, and, moreover, it is not essential, although it is in general desirable, that the surfaces on the two sides be of identical shape.

At 51, Fig. 9, is shown a door which has been moved away from the hangar and then revolved through a suitable angle in relation to the carriage to bring it in line with the wind direction as shown by arrow 53. It is usually customary to enter aircraft at the leeward end of a hangar but it is obvious that as rotation of the doors through a full circle is possible they may be orientated with the wind regardless of its direction.

In some cases it may be desirable as an aid in docking an airship to align the door at an angle with the wind for the purpose of influencing the direction of the air currents. In this case it may also be desirable to adjust the position along the track to obtain the most favorable results.

Fig. 13 shows a modification in which hangar 12 terminates in a square end while tracks 18 are laid at an angle. Door 73 is in the correct angular position for closing the hangar.

In Figs. 10 and 11 are shown alternative arrangements which will accomplish the same purpose as that described. Here the door and carriage are rigidly connected, no rotation between the two being provided for. In order to orientate the door, the track is curved so that by moving the carriage to different points along this track different presentations of the door to the wind are obtained. Track 10, Fig. 11, conforms to the arc of a circle and 71, Fig. 10, to a straight stretch ending in a circular arc. The various arrows are

intended to represent different wind directions. In the use of this scheme, the door is preferably made of a streamline section which is symmetrical fore and aft. Numerous arrangements for turning as a whole a door and carriage which are rigidly connected are obviously possible and need not be separately described.

As an aid in orientating the door, it is intended that instruments be provided to indicate to the operator when an angle exists between the axis of the door and the wind direction. A variety of schemes might be used for this purpose, one of which is shown in Fig. 12. Here apertures 60 and 61 on opposite sides of the wing, also see Fig. 2, communicate through pipes 62 and 63 with opposite legs of differential pressure gauge 64. Only when the door is accurately aligned with the wind will the level of liquid on the two sides be the same. By placing the pivot 14 in a suitable fore and aft position relative to the center of wind pressure, the door tends to line up automatically with the wind in the same manner as a weather vane. It may be found desirable to make use of this effect to obtain automatic control. If this is the case the driving gear for rotating the door on the carriage should be made fully reversible and as free from friction as possible or a clutch be provided to disconnect this driving gear from the door.

Having thus described my invention what I claim as new and desire to secure by Letters Patent is:

1. In a hangar construction, a hangar, closing means for said hangar, means for moving said closing means to points remote from said hangar, and self contained means for rotating said closing means to substantially all points of the compass.

2. In a closing mechanism for an aircraft hangar, a door of streamline section, a carriage for said door, a track for said carriage, means for moving said carriage along said track toward and away from said hangar, and means for rotating said door.

3. In an apparatus of the class described, a hangar, a door adapted to cooperate with the end portion of said hangar to form a closure, the sealing line of said closure lying in substantially a vertical plane through the longitudinal axis of said hangar, a carriage for said door, and means for moving said carriage to a point remote from said hangar along a line which forms an acute angle with said vertical plane.

4. In an apparatus of the class described, a hangar, a door of streamline section adapted to cooperate with the end portion of said hangar to form a closure, the sealing line of said closure lying in substantially a vertical plane through the longitudinal axis of said hangar, a carriage for said door, and means for moving said carriage toward and away from said end portion along a line which forms an acute angle with said vertical plane.

5. In an apparatus of the class described, a hangar, a pair of doors adapted to cooperate with the end portion of said hangar to form a closure, the planes of said doors when forming such closure making acute angles with the longitudinal axis of said hangar, a carriage for each of said doors, and means for traversing each of said carriages along determined paths which are substantially perpendicular to said longitudinal axis.

6. In an apparatus of the class described, a hangar, a pair of doors of streamline section adapted to cooperate with the end portion of said hangar to form a closure, the planes of said doors

when forming such closure making acute angles with the longitudinal axis of said hangar, a carriage for each of said doors, and means for traversing each of said carriages along determined paths which are substantially perpendicular to said longitudinal axis.

5. 7. In an apparatus of the class described, a door comprising a framework and a sheath of streamline section enclosing said framework, a carriage for said door, a mast fastened to said carriage and projecting upwardly into said framework and a bearing member intermediate the upper end of said mast and said door.

8. In a hangar construction, a hangar, a door 15 for said hangar, a carriage for said door, means for moving said carriage and said door toward and away from said hangar and for rotating said door to orientate it in relation to the direction of the existing air currents and means to indicate 20 the position of the door relative to such air currents.

9. In an apparatus of the class described, a door of streamline section, a movable carriage, a ver-

tical axle on said carriage to support said door, means for rotating said door in relation to said carriage and for holding said door in any desired position in relation to said carriage, and means for disconnecting the aforesaid means to permit 5 free rotation of the door.

10. The method of opening an airship hangar and the like comprising the steps of removing a closure member to a point remote from the hangar and from other structures, positioning 10 said member substantially parallel to the direction of the wind and adjusting said positioning in accordance with changes in the direction of the wind.

11. A door for an airship hangar and the like 15 having a pair of edge portions and a pair of face portions, one edge portion being substantially thicker than the other edge portion and of radiused form in cross-section, the faces of the door being substantially tangential to the radiused 20 edge portion and converging toward the other edge portion.

STERLING JOHNSTON.
